Term of patent 14 years

Int. Cl. D24—02

U.S. Cl. D24—1 D

FIG.4

FIG.5

FIG. 1 is a front elevation view of a mouth and dental mirror showing my new design;

FIG. 2 is a rear elevation view of the mirror;

FIG. 3 is a side elevation view showing the right-hand edge of the mirror as viewed in FIG. 1, the left-hand edge elevation view being a mirror image of FIG. 3;

FIG. 4 is a plan view looking down on the top of the inventive mirror, as viewed from plane 4—4, looking in the direction of the arrows;

FIG. 5 is a bottom plan view looking up toward the bottom of the mirror, as viewed from the plane 5—5, looking in the direction of the arrows; and

FIG. 6 is a cross-section taken along line 6—6 of FIG. 2, looking in the direction of the arrows.

I claim:

The ornamental design for a mouth and dental mirror, as shown and described.
